UNITED STATES PATENT OFFICE.

IVER P. BENDIKSON, OF MANDAN, NORTH DAKOTA.

CAR DOOR.

Application filed April 8, 1924. Serial No. 705,093.

To all whom it may concern:

Be it known that I, IVER P. BENDIKSON, a citizen of the United States, residing at Mandan, in the county of Morton and State 5 of North Dakota, have invented certain new and useful Improvements in a Car Door, of which the following is a specification.

This invention relates to improvements in car doors particularly designed for freight 10 cars.

An important object of the invention is to provide a new and improved car door which may be slidably mounted upon a freight car and securely held in position thereon.

15 A further object of the invention is to provide a door of this character which will not become opened or loosened caused by jarring of the car while traveling over the rails.

A still further object of the invention is to 20 provide a door of this character which may be opened or closed with little difficulty and at the same time insure a tight connection.

A still further object of the invention is to provide a door of this character which is 25 comparatively simple in construction, although very durable and efficient for this purpose.

Other objects and advantages of this invention will be apparent during the course 30 of the following description.

In the accompanying drawings forming a part of this specification and in which like numerals are employed to designate like parts throughout the same:

35 Figure 1 illustrates the door embodying my invention mounted on the side of a freight car,

Figure 2 is a similar view showing the door in partially opened position,

40 Figure 3 is a top plan view of my improved door,

Figure 4 is a horizontal section taken on the line 4—4 of Figure 1,

Figure 5 is an end elevation of my invention, and

45 Figure 6 is a vertical sectional view taken on the line 6—6 of Figure 1.

In the drawings, wherein for the purpose of illustration is shown the preferred embodiment of my invention, the numeral 10 generally denotes the side of a freight car which may be used for transporting cattle, grain or any merchandise usually transported in freight cars. My improved door structure 50 generally denoted by the numeral 11 consists of a plurality of longitudinal planks

12 securely fastened by means of a plurality of upright connecting planks 13. I do not wish to limit my invention to this construction however as the door may conceivably be 60 constructed as a solid sliding partition, the construction depending upon the form of merchandise to be carried in the freight car. The type herein illustrated being particularly adapted for stock cars, while I do not 65 wish to limit my invention to this particular application and conceive of applying the door to grain cars and the like. The type of door shown in the accompanying drawings is adapted to slide within a suitable frame 70 built in the side of a freight car and embodies novel securing features.

Mounted in the central portion of the door I provide a sliding bar 14 which is preferably circular in cross section and is actuated 75 by a substantially U-shaped handle lever 15 which extends outwardly beyond the upright members 13 and has its extremities secured to the bar 14. A pair of longitudinally extending bars 16 are secured to the three uprights positioned in the front portion of the bar and are preferably constructed of metal for the purpose of reinforcing the structure of the door. The front pair of uprights 13 each carry a pair of raised guide bars 17 80 adapted to permit movement of a pair of swinging arms 18. The swinging arms 18 are pivotally connected to the center upright near the upper and lower extremities thereof, and have an enlarged engaging head 19 85 formed on the front extremity provided with a rectangular opening in the center.

The swinging arms 18 each carry a pair of tapered bars 20 pivotally connected to the arms as at 21 and adapted to swing 90 therewith. As it is intended to retain the tapered bars 20 in a substantially vertical position I provide a pair of blocks 22 and 23 secured against the uprights 13 to prevent displacement of the said tapered bars. 100 The forward upright of the door carries a pair of arcuate levers 24 positioned near the upper and lower extremities and hingedly secured to the upright by means of straps 25 and pins 26. The inner extremities of 105 the levers 24 carry a pair of swinging bolts 27 hingedly connected to the levers. The outer extremities of the arcuate levers 24 are turned outwardly as at 28 to form actuating clips to permit the levers to be readily 110 swung about their pivot pins.

The bolts 27 are adapted to engage suit-

able sleeves 29 formed on the outer portion of brackets 30 secured to the door frame. In order to prevent movement of the levers 24 when in the closed position I provide a 5 pair of swinging cam members 31 pivoted adjacent the levers and adapted to be positioned in the retaining straps 25 and prevent displacement of the levers whereby the bolts 27 are held in the sleeves 29 as shown 10 in Figure 1.

The upper portion of the door frame has a metallic strip 32 secured thereon, the outer extremity being turned to provide hinged joints. A swinging plate 33 has co- 15 acting turned edges adapted to align with the said hinged joint and adapted to receive a circular hinge rod 34 forming an axis about which the plate 33 may be rotated. The turned edges of the co-acting 20 plate are constructed to permit a space 35 to be formed between the supporting strip and hinged plate thus enabling the plate 33 to be moved longitudinally as well as swung easily about the rod. The swinging plate 25 33 is provided with rectangular openings 36 adapted to receive the extremities of the tapered bars 20 one edge of the opening being provided with a tapered slot for the purpose of receiving the shank of a pair of retaining bolts 37 secured to the door and provided 30 with enlarged heads 38. A retaining knob is also secured to the metallic strip as denoted by the numeral 39 and is adapted to engage a swinging latch 40 pivoted to the 35 plate 32 for the purpose of preventing movement of the swinging plate in closed position.

The lower extremity of the door frame carries a bracket 41 bolted or otherwise secured thereto, intermediate portions of the bracket being bent outwardly as at 42 for the purpose of receiving the lower tapered bars 20 and assisting the door closure. In order to prevent movement of the U-shaped 45 handle lever 15 I provide a hinged bracing plate 43 hingedly mounted upon the central upright and provided with a recess 44 at its extremity, the said recess being adapted to engage the handle lever 15 in the closed position. A pair of extending prongs are formed on the extremity of the bracing plate 43 and rest upon the longitudinal bars 16 when the plate is in the closed position and engaging the lever 15. The end jamb 50 55 of the door frame is provided with a groove in the central portion thereof covered by a cover plate 45 secured in the central portion of the jamb and adapted to receive the circular bar 14.

In operation, when the car is being transported the locking devices are in closed position and securely retain the door in position. When it is desired to open the door 60 as shown in Figure 2 the bracing plate 43 is swung outwardly permitting the U-shaped

lever 15 to be moved longitudinally toward the rear of the door and releasing the bar 14 from the door frame. The next operation consists in swinging the cam members 31 away from the retaining straps 25 and 70 swinging the arcuate levers 24 causing the bolts 27 to be withdrawn from the sleeves 29. The arms 18 which have their extremities positioned over the sleeves 29 are then forced upwardly and released from the 75 sleeves and swung toward the center of the door carrying the tapered bars 20 therewith and releasing them from the bracket 41 and plate 33, the plate 33 being forced longitudinally thus releasing same from the 80 bolts 37 and freeing the door.

It is to be understood that the form of my invention herewith shown and described is to be taken as the preferred example of the same, and that various changes as to the 85 shape, size and arrangement of parts may be resorted to without departing from the spirit of the invention or the scope of the subjoined claims.

Having thus described my invention, I 90 claim:

1. A locking device for a car door comprising a plurality of uprights secured to the said door, a pair of swinging arms pivotally connected to the said uprights, a plurality of tapered bars hingedly connected to the swinging arms, means associated with the bars for engaging the said tapered bars, guide plates mounted on the uprights for guiding the said swinging arms, means for retaining the swinging arms in position when the door is closed, and means for preventing removal of the said arms.

2. A locking device for a car door comprising a plurality of upright bars secured 105 to the outer side of the door, a pair of swinging arms hingedly connected to one of the uprights, a plurality of tapered bars pivotally connected to the said swinging arms, brackets secured to the door frame adapted 110 to engage the extremities of the swinging arms, movable bolts adapted to engage the said brackets and prevent displacement of the swinging arms in a closed position, 115 means associated with the door frame for engaging the extremities of the tapered bars, and means for preventing removal of the said bolts.

3. A locking device for a freight car door comprising a plurality of longitudinal beams, 120 a plurality of supporting upright beams, a pair of swinging arms pivotally connected to one of the uprights, a plurality of strips mounted upon the uprights and adapted to form guides for the swinging arms, a plurality of tapered bars pivotally connected to the intermediate portions of the swinging arms, a plurality of brackets secured to the frame 125 of the door, means for connecting the extremities of the swinging arms with the 130

said brackets, a pair of arcuate levers pivotally mounted upon the extremity of the door, swinging bolts connected to the extremities of the arcuate levers, means for inserting the said bolts within the said brackets to prevent removal of the swinging arms, a clamp secured to the lower portion of the door frame, a swinging plate having recesses formed therein secured to the upper portion of the door frame, and a plurality of lugs secured to the upper portion of the door adapted to engage grooves in the swinging plate, and means for retaining the said plate in a downward position.

15 4. A locking device for a freight car door comprising a plurality of upright beams secured to the outer side thereof, a pair of swinging arms pivoted to one of the uprights, guide strips secured to the uprights and adapted to guide the swinging arms, a plurality of tapered bars pivotally connected to the intermediate portion of the swinging arms, enlarged portions formed on the extremities of the swinging arms and having recesses formed therein, a pair of brackets secured to the door frame, extension sleeves formed on the outer portion of the

brackets, the said sleeves being adapted to engage the recesses in the extremities of the swinging arms, a pair of arcuate levers pivotally mounted to the forward upright of the door, swinging bolts secured to the extremities of the arcuate levers, the said bolts being adapted to engage the sleeves formed on the brackets and prevent removal of the swinging arms in the closed position, swinging cams secured adjacent the arcuate levers adapted to prevent movement of the same in the closed position, a bracket secured to the lower portion of the door frame and adapted to engage the extremities of the tapered bars, a swinging plate secured to the upper portion of the door frame provided with recesses therein, the said recesses being adapted to engage the extremities of the upper tapered bars, tapered grooves formed in the said swinging plate adapted to engage the extension bolts formed on the upper portion of the door, and means for preventing movement of the plate.

In testimony whereof, I have affixed my signature.

IVER P. BENDIKSON.
